Primary Examiner — Ian Simmons*Assistant Examiner* — Shannon Morgan(74) *Attorney, Agent, or Firm* — ALG Intellectual Property, LLC(57) **CLAIM**

The ornamental design for a display device with graphical user interface, as shown and described.

DESCRIPTION

The FIGURE is a front view of a display device with graphical user interface showing our new design. The broken lines shown in the FIGURE represent portions of the display device with graphical user interface that form no part of the claimed design.

1 Claim, 1 Drawing Sheet
